LIGHT REFLECTING MEANS

Charles Daniel Ryder, Covington, Ky., assignor
to The National Colortype Company, Bellevue,
Ky., a corporation of Kentucky

Application May 12, 1936, Serial No. 79,299

28 Claims. (Cl. 40—130)

The present invention relates to light reflecting devices of the character adapted to reflect incident light, one object being to provide improvements in devices of this class by which to greatly increase their usefulness and effectiveness for different purposes.

A further object of the invention is to provide an improved device of this character for reflecting light of different colors in such a manner as to more readily attract attention when used for various purposes as, for example, in connection with warning or direction indicating signals, advertising or display signs, and similar purposes.

A further object of the invention is to provide an improved light reflecting device comprising a lens and a reflector having different portions thereof of different light reflecting properties and definitely and systematically arranged and constructed to cause the light beam reflected by said device to vary systematically in appearance as the light source is moved across the field of the lens.

A further object of the invention is to provide a construction for such devices by means of which they may be made to return a reflection varying in intensity or in color during the movement of the light source, so that the varying reflection will attract attention.

A further object of the invention is to provide an improved light reflecting unit for reflecting incident light, which can be assembled in a sign in varying numbers, and according to a predetermined design or pattern and is brought into reflecting action successively, one unit after another, to make the sign progressively reflecting and thus attract attention to it.

A further object of the invention is to provide an improved unitary light reflecting device of the character indicated above, designed for ready application to a sign board or other support, and having an improved arrangement of parts of a simple and practical nature, which can be manufactured at a comparatively low cost.

To these and other ends the invention resides in certain improvements and combinations of parts, all as will be hereinafter more fully described, the novel features being pointed out in the claims at the end of the specification.

In the drawing:

Fig. 1 is a longitudinal section through one of the improved light reflecting units;

Fig. 2 is a diagrammatic view showing the relationship of the lens means and reflector and disclosing one illustration of the application of different colors to the reflector, and also show-

ing the reflection of rays incident substantially parallel with the optical axis;

Fig. 3 is a similar view but showing the reflection of rays incident at a substantial angle to the optical axis;

Fig. 4 is a front view of the reflector shown in Fig. 2, illustrating concentric bands or zones of different colors in surrounding relation with respect to the central clear or white spot of the reflector for reflecting white light;

Fig. 5 is a front view of a reflector showing one color only applied thereto;

Fig. 6 shows another modification, illustrating a reflector having relatively narrow alternately arranged bright and dark zones;

Fig. 7 discloses still another modification in which the reflector is provided with vertically disposed parallel stripes of alternate bright and matte surfaces on the metal of the reflector;

Fig. 8 shows a series of reflectors similar to that disclosed in Fig. 5, in which the diameter of the central or clear spot for reflecting white light is progressively increased from left to right, and

Fig. 9 is a diagrammatic view illustrating a portion of a sign in which the different letters shown have reflectors, the central clear spots of which differ in size in a predetermined order.

The same reference numerals throughout the several views indicate the same parts.

In the embodiment of the invention disclosed in Fig. 1, 10 comprises a lens body of suitable glass having a front face 11 and a rear face 12, one or both of which may be generally convex. Preferably the front face 11 is of convex curvature and the rear face may be plane or convex.

Associated with the lens is a concave reflector 13, spaced in rear of the convex rear face 12 of the lens and concentric with the optical axis of the lens, the reflector being preferably placed with its vertex at the focal point 14 of the axially parallel rays as shown.

Although any suitable reflector and lens means may be employed in connection with the present invention, it is preferred to make use of corresponding elements having the general characteristics of those shown in U. S. Patent No. 1,872,643, for a Light reflecting device.

The lens is secured within the front end of a suitable housing 15, adapted to be inserted within an aperture of a support or sign plate such, for example, as the plate shown at 16 in Fig. 9. The housing is provided with a shoulder 17 for engaging the front side of the plate and has on its rear end a threaded part 18 for extension through an opening in a retaining member for 50

the housing not shown, but adapted to engage the rear face of the sign plate, the housing being clamped in position on the sign plate and detaining member by a nut when screwed upon the threaded part 18, as well understood in the art.

In the present disclosure the reflector is preferably mounted within the housing and suitably supported therein as, for example, by means of the forwardly extending cylindrical element 19, having a flange 20 seated upon a shoulder 21 of the housing, upon which it is held preferably by a layer of cement 22 or other suitable material adapted to form a sealed joint between the flange and the lens element. The lens element is held against outward displacement preferably by the inwardly turned portion 23 of the housing as shown in Fig. 1. However any suitable lens and reflector mounting means may be provided, other than that shown and described.

The reflectors used within the housing and diagrammatically illustrated in Figs. 2 to 8, inclusive, are preferably of similar construction to that shown in Fig. 1, with the cylindrical supporting element 19 omitted for the sake of clearness.

Disposed on the inner faces of the reflectors shown in Figs. 2, 3, and 4 are a series of concentrically arranged zones of different colors indicated at 24, 25, and 26, and comprising in the present instance blue, red, and green, respectively, although the particular position of the different colors one relative to another and the colors themselves may be varied as desired. The colors may be applied to the reflector in any preferred manner or by the use of any means suitable for the purpose, such, for example, as transparent lacquers, or the like. However the zones or bands of color may constitute preformed light transmitting bodies placed on and united with or secured upon the reflector by the use of a suitable transparent binder.

The reflecting units when placed in a highway sign are capable of being rendered luminous and visible by the rays or concentrated beam of a motor vehicle headlight when the vehicle is approaching the sign at a substantial distance therefrom. With the sign pointed substantially along the road, the vehicle, at a considerable distance from the sign, will be located approximately in line with the optical axis of the reflecting unit so that the rays incident in a direction substantially parallel with the axis will be focused on the clear spot 27 of the reflector. However as the vehicle continues to approach the sign the angle between the incident rays and the optical axis will be progressively increased whereby the apex of the cone of light will travel obliquely across the reflector from the central point 14 in Fig. 2 to the point 14a shown in Fig. 3. In other words, the apex of the cone of light when focused at the center of the reflector will afford a white light following which the concentric color zones 24, 25, and 26 will be successively illuminated as the apex of the cone moves obliquely across the reflector from the position shown in Fig. 1 to that shown in Fig. 2. Likewise, the rays of light will be focused upon the centers of the reflectors shown in Figs. 5, 6, and 7 with the apex of the cone moving across the reflectors to illuminate the same. The sign may be positioned, of course, more transversely of the road than referred to above so that the white reflection from the central portion of the reflector is both preceded and followed by colored reflections from the opposite marginal reflecting areas.

In the modification shown in Fig. 5 the reflector 13a is provided at its center with a clear or bright spot 27a similar to that shown in Fig. 4, although in this case the reflector has only one color applied thereto, preferably red, as indicated at 28. Light reflecting units containing this reflector are particularly adapted for use in highway signs as danger or warning signals, although they may be used for other purposes as well.

In the modification shown in Fig. 6 the reflector 13b has a series of alternate light and dark zones 29 and 30 respectively, the zones being concentrically arranged around an axially disposed clear or bright spot 27b at the center of the reflector. The several zones may constitute a part of the surface of the reflector or may be formed by applying coatings of light and dark material thereto. When this particular reflector is used with the unit shown in Fig. 1, a blinking effect will result, as the apex of the cone of light 20 travels from the central or bright spot 27b obliquely across the face of the reflector to successively illuminate the light zones 29.

In the modification shown in Fig. 7, instead of employing concentrically arranged bands or zones of contrasting shades or colors, the face of the reflector 13c is provided with parallel vertically extending stripes 31 and 32 of alternate bright and matte surfaces on the metal of the reflector, the bright surfaces reflecting specularly and the matte surfaces reflecting diffusely. With this reflector the light reflecting units will alternately appear bright and dull as the apex of the cone of light traverses the reflector arc.

It will be understood, however, that instead of providing alternate bright and matte surfaces on the reflector 13c the parallel stripes may be formed by applying two or more colors to the reflector or any combination of tints and colors which may be found useful.

In the modification shown in Fig. 8 a series of reflectors 13d is provided, having centrally disposed bright areas 33 for reflecting white light, these areas being progressively increased in size from left to right, as shown. The remaining portions of the reflectors have applied thereto a single color, preferably red, as indicated at 34. However, if desired, a plurality of colors may be applied to each reflector and arranged around the central bright spot 33, either in concentrically disposed zones or otherwise, as preferred.

By constructing a sign with a plurality of the light reflecting units shown in Fig. 1 having reflectors differing in the order shown in Fig. 8, beginning with the unit having the smallest central reflecting area and ending with the one having the largest of said areas, the result will be that, in a given position of the light source, the letters of the sign will differ in appearance and such difference will progress from letter to letter in succession as the light source is moved across the face of the sign.

It will be understood, however, that the outer areas 34 of the reflectors shown in Fig. 8 which surround the central areas 33 may have different tints or colors applied thereto, either in the form of concentric zones or bands, or otherwise, as preferred.

It will be apparent that a sign constructed along these lines, for illumination by incident light from an exterior source, will be extremely advantageous as an advertising medium, since the reflecting units may be so arranged on the sign as to represent various characters, word combinations, or designs. This is true regardless

of whether, the sizes of the central reflecting areas of the units are progressively increased in the manner indicated in Fig. 8 or not.

In the arrangement shown in Fig. 9 the characters or letters indicated at 35, 36, and 37 are each provided with a series of reflecting units, of which the reflectors only are shown. The reflectors illustrated in this view are provided with progressively increasing central areas as shown in Fig. 8. For example, the reflectors 35a of the letter or character 35 shown in Fig. 9 have relatively small central areas 35b. The reflectors 36a of the next succeeding character 36 have slightly larger central areas 36b, while the reflectors 37a of the letter or character 37 are providing with still larger central reflecting areas 37b. It will be apparent therefore that with a sign constructed in this manner, the characters of the sign will be successively different in appearance when illuminated by the rays from the head light of a motor vehicle approaching the sign. In other words, if the sign embodies a series of the reflecting units shown in Fig. 1 arranged to form the letters of one or more words, the latter will appear to be traced out, letter by letter, when the motor vehicle is approaching the sign and moving at an increasing angle to the optical axes of the reflecting units.

With the reflector shown in Fig. 4, a bright or white light, preferably, will first be flashed, as the apex of the cone of light strikes the central area 27, and thereafter the colors blue, green, and red will be progressively displayed in rapid succession. The use of this particular reflector or one or more similar thereto, but having different combinations of colors will make it possible to provide a sign which will readily attract attention, whether it be used for advertising, signalling, or other purposes.

This is also true of the reflector shown in Fig. 6, which when used in the reflecting unit shown in Fig. 1 will, as previously stated, function as a blinking sign, or one on which the light will appear to be turned on and off in rapid succession as the clear zones 29 are progressively illuminated by movement of the apex of the cone of light from the central spot 27b obliquely across the face of the reflector.

In the use of the reflector shown in Fig. 7, the bright or mirror-like surfaces 31 will reflect specularly and the dark or matte surfaces 32 diffusely, as the apex of the cone of light travels from the center of the reflector obliquely across the face thereof.

It will be understood that a series of the units shown in Fig. 1 with any one of the different types of reflectors provided can be used exclusively in a sign and arranged in any preferred order, or in such a manner as to form an attractive design for illumination by an external light source.

In the use of a plurality of the units with reflectors having central areas for reflecting white light of gradually increasing size and colored areas correspondingly diminishing in size as indicated, for example, in Fig. 8, an extremely effective sign can be constructed for different purposes and one which will be particularly useful in the field of advertising.

It will be further understood that signs varying widely in character or design may be formed with light reflecting units having either of the modified forms of reflectors shown, or with a combination of two or more of the same, and for whatever purpose desired.

Any suitable external light source, other than the headlight of a motor vehicle may be provided for illuminating the sign and maintained at the desired distance therefrom such, for example, as a fixed or an oscillating, or revolving light source 5 of any preferred type.

Although I have shown the different color zones and the light and dark zones of the several modifications illustrated in Figs. 4 to 8 inclusive on a reflector spaced from the lens means, it will be 10 understood that the materials applied to the reflector may, if desired, be applied in the same order to the rear face of a suitable lens or light refracting unit.

By the term zone in the claims I mean defined areas comprising straight or curved bands, or stripes, or belts, or spaces of substantially uniform width, or with margins that are substantially parallel although the latter requirements are not essential, but preferable. The said 15 areas or zones are not limited to encircling areas. The term may be also defined as a belt or area distinguished from adjacent areas by different colors. Such zones are preferably of substantially equal cross section and are formed with 20 parallel margins to form narrow rectangular areas, or circular areas of substantially uniform width.

I claim:

1. A light reflecting device including a lens 30 corrected for spherical aberration to render the same optically effective over substantially the full diameter thereof, and a reflector behind said device, a plurality of light transmitting materials comprising zones of different colors, said zones 35 being in such relation one relative to another whereby to be successively illuminated by incident light rays entering the lens at progressively increasing angles with the optical axis.

2. A light reflecting device comprising a lens 40 corrected for spherical aberration to render the same optically effective over substantially the full diameter thereof, a reflector disposed rearwardly of said lens and having a central area for reflecting white light, and light transmitting 45 means containing coloring matter disposed in front of the reflector around said central area and forming one or more zones of color for illumination by incident light rays entering the lens at progressively increasing angles with the 50 optical axis.

3. A light reflecting device comprising a lens, a curved reflector disposed rearwardly of said lens, and light transmitting means containing coloring matter applied to the face of the reflector and 55 forming one or more zones of color concentric with the optical axis of the lens for illumination by incident light rays entering the lens at progressively increasing angles with the optical axis.

4. A light reflecting device comprising lens 60 means, a curved reflector spaced from the lens means in rear thereof and having a limited area for reflecting white light, and light transmitting means applied to the face of the reflector and forming a plurality of concentrically arranged 65 color zones of different colors substantially surrounding said area, said area and color zones being successively illuminated by light rays incident in a direction substantially parallel with the optical axis of the lens means and moving across 70 the reflector at progressively increasing angles with said axis.

5. Light reflecting means provided with reflecting devices each comprising a single lens and a curved reflector in rear thereof, said lens hav- 75

- ing a relatively short focal length and having a face thereof aspherically curved to provide correction for spherical aberration in rays incident in a direction substantially parallel with the lens axis for reflecting said rays back in the direction of the light source with low spread and high intensity, and light transmitting means interposed between the lens and reflector and forming one or more zones of color concentric with the optical axis of the lens.
6. Light reflecting means provided with reflecting devices each comprising a single lens and a curved reflector in rear thereof, said lens having a relatively short focal length and having a face thereof aspherically curved to provide correction for spherical aberration in rays incident in a direction substantially parallel with the lens axis for reflecting said rays back in the direction of the light source with low spread and high intensity, said reflector having a central area for reflecting white light and having light transmitting means forming one or more zones of color substantially surrounding said central area.
7. Light reflecting means provided with a series of light reflecting units each including lens means and a reflector, the reflectors having central areas for reflecting white light and outer surrounding areas for reflecting colored light, said central areas being progressively increased in size in a predetermined order.
8. Light reflecting means having a plurality of characters for illumination by an exterior light source, said characters each including one or more light reflecting units, said units each including lens means and a reflector, and the reflectors having central zones for reflecting white light and outer colored zones formed of light transmitting material, the central zones of the reflectors of each character differing in size from the central zones of the reflectors of the remaining characters.
9. Light reflecting means having a plurality of characters for illumination by an exterior light source, said characters each including one or more light reflecting units, said units each including lens means and a reflector, said reflectors having central zones for reflecting white light and having outer concentrically arranged zones formed of light transmitting material of one or more colors applied to the reflectors, the central zones of the reflectors of each character differing in size from the corresponding zones of the reflectors of the remaining characters.
10. A light reflecting unit for use in a sign, comprising a biconvex lens corrected for spherical aberration to render the same optically effective over substantially the full diameter thereof and having its focal point on the optical axis in rear of the lens, a concave reflector spaced rearwardly of the lens with its vertex substantially at said focal point, and light transmitting zones of one or more colors interposed between the lens and the reflector and in such relation whereby to be successively illuminated by incident light rays entering the lens at progressively increasing angles with the optical axis.
11. A light reflecting unit for use in a sign, comprising a biconvex lens having its focal point on the optical axis in rear of the lens, a concave reflector spaced rearwardly of the lens with its vertex substantially at said focal point, and light transmitting means applied to the face of the reflector and forming a plurality of zones of different colors concentric with the optical axis of the lens.
12. A light reflecting device comprising a lens corrected for spherical aberration to render the same optically effective over substantially the full diameter thereof, and a reflector having applied to different portions thereof zones of light transmitting material capable of affording a high degree of illumination and definitely and systematically arranged on the reflector and constructed to cause the light beam reflected by said device to vary systematically in appearance with variation of the angle of incidence of the light on said device, said different portions of the reflector comprising light transmitting means containing different coloring materials.
13. A light reflecting device comprising a lens corrected for spherical aberration to render the same optically effective over substantially the full diameter thereof, and a reflector having applied to different zones thereof zones of transparent material having different light reflecting properties and arranged in succession across the said reflector in the path of a light beam projected thereon by said lens from a light source moving across the lens field, whereby to produce a predetermined variation in the appearance of light beams reflected by said device during said movement of the light source, said different portions of the reflector comprising light transmitting means containing different coloring materials.
14. A light reflecting device comprising a lens, and a reflector having different portions thereof of different light reflecting properties arranged in different zones of different color substantially concentric with the optical axis of said lens and reflector, so as to lie successively in the path of a beam projected by said lens from a light source moved across the field of said lens.
15. A light reflecting device comprising a lens corrected for spherical aberration to render the same optically effective over substantially the full diameter thereof, and a reflector in rear of said lens having different zones thereof of different color definitely and systematically arranged and constructed whereby to cause the light beam reflected by said device to vary systematically in appearance with variation of the angle of incidence of the light on said device.
16. A light-reflecting device comprising a lens corrected for spherical aberration to render the same optically effective over substantially the full diameter thereof, and a reflector in rear of said lens having different portions thereof of different color arranged in different zones substantially concentric with the optical axis of said lens and reflector, so as to lie successively in the path of a beam projected by said lens from a light source moved across the field of said lens to cause the light beam reflected by said device to vary systematically in appearance with variation of the angle of incidence of the light on said device.
17. A light reflecting device comprising a lens having a face thereof aspherically curved more sharply adjacent its center than its peripheral area to correct for spherical aberration and render said lens optically effective over substantially the full diameter thereof, and a reflector in rear of said lens having different portions thereof of different color arranged in different zones substantially concentric with the optical axis of said lens and reflector, so as to lie successively in the path of a beam projected by said lens from a light source moved across the field of said lens.
18. A light reflecting device, comprising a lens

having a face thereof aspherically curved more sharply adjacent its center than its peripheral area to correct for spherical aberration and render said lens optically effective over substantially the full diameter thereof, and a reflector in rear of said lens, colored materials in front thereof having different zones thereof definitely and systematically arranged and constructed whereby to cause the light beam reflected by said device 10 to vary systematically in appearance with variation of the angle of incidence of the light on said device.

19. A light reflecting device, comprising a lens corrected for spherical aberration to render the same optically effective over substantially the full diameter thereof, and a reflector at the rear of said lens having colored materials in front thereof in different zones thereof arranged so as to lie successively in the path of a beam projected 20 by said lens from a light source moved across the field of the lens, said zones being formed of material adapted to cause the light beam reflected by said device to vary systematically in appearance with variation of the angle of incidence 25 of the light on said device, the material of some of said portions serving to reflect white light.

20. In combination, a lens, a reflector spaced therefrom behind the lens at the focal point of said lens, and a plurality of intermediate media 30 of diverse colors adapted to form defined colored zones that are light-transmitting whereby said lens will appear in a succession of different colors as the exterior light source passes transversely of the axis of said lens.

21. In a method of giving a vari-colored appearance to a single lens so that it is successively colored with different colors, the steps of (a) moving a beam of light rays transversely of the face of the lens; (b) converging said rays to a focal point behind the lens so that said focal point will move in an arc behind the lens, and (c) presenting defined different colored zones in the path of said focal point whereby the reflected incident light will appear as original sources of colored light of successively different colors as the angular position of the beam of light changes with respect to the axis of the lens.

22. In a method of delivering vari-colored beams of reflected incident light so as to appear as originating from sources of vari-colored light, the steps of (a) directing a beam of white light through a lens and moving the source of said light transversely of the axis of said lens; (b) converging said light to a defined focal point behind the lens; (c) presenting defined different colored zones in the path of said focal point so that the reflected incident light will appear as original sources of colored light of successively different colors as the angular position of the beam of light changes with respect to the axis of the lens; and (d) reflecting the light back

through said colored zones and said lens as the focal point of the light passes over the surface of the reflector.

23. In a method of giving a vari-colored appearance to a single lens so that it successively appears to have a different light-reflecting character, the steps of (a) moving a beam of light rays transversely of the face of the lens; (b) converging said rays to a focal point behind the lens so that said focal point will move in an arc behind the lens, and (c) presenting defined different appearing zones in the path of said focal point whereby the reflected incident light will appear as original sources of different appearing light of successively different light-reflecting powers as the angular position of the beam of light changes with respect to the axis of the lens.

24. In an autocollimating device, the combination of a refractory element having a convex objective plane and a reflector element arranged opposite the said objective plane impinged by light rays projected against the said refractory element and focused therethrough, coatings of translucent material of varied colors in zones applied to the said reflecting element, each of 25 said varied colors singularly producing rays of varied hues in zones.

25. In an autocollimating device, the combination of a lens having a parabolic objective surface and a concave reflector of greater diameter than 30 the said lens providing a reflecting surface impinged by light rays focused through the said lens, means covering zones of the said reflecting surfaces singularly affording varied colored light reflections in different zones.

26. In an autocollimating device, the combination of a lens having a convex outer surface and a concave reflector surface impinged by light rays focused through the said lens, layers of translucent colored materials vertically arranged 40 in zones over the reflecting surface and providing an irradiant illumination of varied hues in zones.

27. In an autocollimating device, the combination of a lens having a convex objective surface and a concave reflecting surface impinged by 45 light rays focused through the said lens, means on the said reflecting surface converting the light rays projected thereagainst into varied hues in zones, each hue being determined by the angle of the light rays projected thereagainst in each 50 zone.

28. In an autocollimating device, the combination of a lens having a convex objective surface and a concave reflector impinged by light rays focused through the said lens and passing horizontally across the surface of the said reflector, zone means covering the said surface providing varying single hues in zones of reflected illumination as the said focused rays traverse the said reflecting surface.

CHARLES DANIEL RYDER.
